BABY CRADLE

Joseph John Billhimer, Sr., 5804 S. Coffman-Pico Road,
Rivera, Calif.

Filed Dec. 15, 1958, Ser. No. 53,771

Term of patent 14 years

(Cl. D5—5)

Fig. 1.

Fig. 2.

Fig. 3.

Fig. 1 is a front perspective view of a baby cradle embodying my new design. The opposite end of the cradle is identical with the end shown.

Fig. 2 is a top plan view of the same.

Fig. 3 is a rear elevational view of the same.

I claim:

The ornamental design for a baby cradle, substantially as shown and described.
